UNITED STATES PATENT OFFICE

JOHN E. MOTT, OF ADRIAN, MICHIGAN, ASSIGNOR TO MERCHANTS ADVERTISING COMPANY, OF ADRIAN, MICHIGAN, A CORPORATION OF MICHIGAN

DESIGN FOR A CLOCK CASING

Application filed December 26, 1930. Serial No. 38,123. Term of patent 14 years.

To all whom it may concern:

Be it known that I, JOHN E. MOTT, a citizen of the United States, and resident of Adrian, county of Lenawee, State of Michigan, have invented a new, original, and ornamental Design for a Clock Casing, of which the following is a specification, reference being had to the accompanying drawing, forming a part thereof.

Fig. 1 is a front elevation of a clock casing showing my new design; and

Fig. 2 is a top plan view of the clock casing shown in Fig. 1.

I claim:

The ornamental design for a clock casing as shown.

In testimony whereof I have hereunto signed my name to this specification.

JOHN E. MOTT.
